Des. 183,075
Patented June 17, 1958

183,075

PLASTIC SHEET MATERIAL

Russel Wright, New York, N. Y.

Application November 18, 1957, Serial No. 48,528

Term of patent 14 years

(Cl. D87—3)

The single figure of the drawing is a plan view of plastic sheet material showing one complete repeating unit of my new design.

I claim:

The ornamental design for plastic sheet material, substantially as shown.
